COMBINED KEYBOARD AND ELECTRONIC DATA PRINTER

Philip H. Stevens, Syracuse, and David O. Chase, Camillus, N.Y., and Roger A. Schindler, Allison Park, Pa., assignors to SCM Corporation, a corporation of New York

Filed Oct. 17, 1962, Ser. No. 72,137

Term of patent 14 years

(Cl. D64—11)

Fig. 3

Fig. 4

FIGURE 1 is a front perspective view of a combined keyboard and electronic data printer showing our new design;

FIGURE 2 is a front elevational view thereof;

FIGURE 3 is a right side elevational view thereof;

FIGURE 4 is a top plan view thereof; and

FIGURE 5 is an exploded elevational view of the side opposite to that of FIGURE 3 showing the keyboard, printer and power unit in separated condition.

The power unit housing has a bottom inset flange continuous completely around the unit and the perforated grill work which extends across the top also curves across the upper rear edge and extends down the back of the power unit housing to the edge of the inset above the flange, the back of the power unit being otherwise plain and unornamented.

The dominant features of our design are shown in full lines.

We claim:

The ornamental design for a combined keyboard and electronic data printer, substantially as shown and described.
